DISPENSING ARRANGEMENT

Louis V. Aronson, Newark, N. J., assignor to Art Metal Works, Inc., a corporation of New Jersey

Application September 16, 1933, Serial No. 689,779

2 Claims. (Cl. 221—67)

My invention relates to the dispensing art and, more particularly, to an arrangement for supplying liquid fuel to a pyrophoric lighter casing.

In accordance with my invention, a supply of liquid fuel is retained in a container of novel construction, such container being actuatable to discharge a desired quantity of the liquid fuel into the lighter casing in a simple and efficient manner.

Further advantages, objects and characteristics of my invention will become apparent from the following detailed description.

My invention resides in the dispensing arrangement, combinations and features of the character hereinafter described and claimed.

For an illustration of one of the forms of my invention, reference is to be had to the accompanying drawing, in which:

Figure 1 is a plan view of a fuel-containing receptacle as constructed in accordance with my invention;

Fig. 2 is a side elevational view of the receptacle shown in Fig. 1;

Fig. 3 is a vertical sectional view, partly in elevation, showing the receptacle of Figs. 1 and 2 associated with a pyrophoric lighter; and

Fig. 4 is a vertical sectional view of a part of the dispensing arrangement.

In general, my invention relates to an arrangement including a fuel-containing receptacle or container with which the casing of any suitable pyrophoric lighter may be associated whereupon a desired quantity of fuel is pumped therewith. The invention has particular application to a fuel receptacle which is adapted to be supported in upright position on a counter or the like so that the lighter casing, in fuel-transferring relation, may be associated therewith and supported thereby.

Referring to the drawing, R represents any suitable container or receptacle having a bottom wall 1 which preferably is flat and of substantial area so as to form a substantial supporting surface to be disposed upon a store table, counter, or the like. As herein shown, the receptacle R comprises rear and front walls 2 and 3, these walls being joined by suitable side walls so as to form a casing of suitable configuration.

The container R has a top wall 4 which, approximately centrally thereof, is provided with an opening for the reception of a flanged bushing 5, adjacent surfaces of said top wall 4 and bushing 5 being soldered or otherwise suitably secured together. As illustrated, the bushing 5 comprises a threaded lower section to which the

lower section of a nipple 6 is threaded, a suitable gasket 7 preferably being disposed between flanged surfaces of the bushing 5 and nipple 6.

The upper portion of the nipple 6 preferably comprises a plurality of stepped surfaces 6a and 6b, each of these surfaces being threaded as clearly indicated in Figs. 3 and 4. Adapted to be threaded to one of these stepped surfaces is a closure cap 8 which may be sealed with respect to the nipple 6 in any suitable manner as, for example, by the provision of a gasket 9.

The nipple 6 is provided with a longitudinal passage through which extends a tube 10, these parts being permanently secured together in any suitable manner. The tube 10 extends downwardly within the receptacle R and terminates immediately adjacent the bottom thereof. As shown, said tube 10 is free and unobstructed throughout the length thereof whereby liquid fuel contained in the receptacle R may readily be passed upwardly therethrough.

Any suitable arrangement may be utilized for thus passing fuel from the receptacle R into and through the tube 10. Thus, for example, the front wall 3 of said receptacle R may be of the general type utilized as the bottom of an oil can for expelling the contents thereof. If so, said front wall 3 may be formed with a circular bead section 3a of U-configuration in section as shown in Fig. 3. This bead section 3a forms the boundary for a diaphragm section 3b which is fashioned in suitable manner so that it acts piston-fashion on the contents of the receptacle R when pressure is applied from left to right thereof, Fig. 3. It is obvious that the diaphragm section 3b when actuated in this manner serves to force liquid upwardly through the tube 10.

In Fig. 3, there is illustrated a pyrophoric lighter mechanism of well known commercial type. In general, this lighter mechanism comprises a fuel casing 11 which carries suitable actuating parts for the lighting mechanism, such parts comprising a pivoted snuffer lever 12 adapted to be actuated by a depressible member 13 having a spring-controlled plunger 14 depending therefrom into said casing 11. The snuffer lever 12 engages the top of a tube 13a through which extends a wick 14a utilized for transferring fuel to the ignition region from the interior of the lighter casing 11. As is usual with lighter casings of the character illustrated, the bottom wall 15 thereof may be formed with a flanged circular opening 15a internally threaded for the reception of the threaded shank of the casing closure cap, not shown.

When the fuel content of the lighter casing 11 becomes exhausted, the above noted closure cap may be removed from the bottom casing wall 15 whereupon the lighter casing 11, at its opening 5 in the bottom wall thereof, may be threaded to the upper threaded section 6b of the nipple 6 as shown in Fig. 3. Thereupon, the diaphragm section 3b of the front wall 3 may be actuated repeatedly to force or pump a desired quantity of fuel upwardly through the tube 10 and thence 10 into the casing 11. During this pumping operation, it is desirable that the lighter section 13 be held in its depressed position whereby the snuffer lever 12 is held in its elevated position. By so 15 doing, the upper end of the wick 14a is exposed to view and, accordingly, the operator may ascertain when the upper wick section becomes moist by reason of admission of fuel to the casing 11. When this occurs, the operator may be reasonably 20 sure that a sufficient quantity of fuel has been introduced into the casing 11 and, at this time, the pumping operation may be discontinued. Thereafter, the casing 11 may be unthreaded from the nipple 6 and the closure cap for said casing 25 rethreaded thereto.

The fuel filling openings of lighter casings as constructed by different manufacturers vary somewhat as regards the diameter thereof. It is for this reason that a plurality of stepped surfaces 30 6a, 6b are provided on the nipple 6. By so doing, the fuel receptacle R is adapted to be associated, in fuel-transferring relation, with lighters having fuel-filling openings of different diameters and, accordingly, the use of the dispensing arrangement may be much more extensive than would otherwise be the case.

The closure cap 8, at the upper end thereof, may be provided with a tapered section 8a useful as a tool for insertion in the usual slot formed 40 in the lighter casing closure cap when said last named closure cap is to be removed from or applied to the lighter casing.

It shall be understood that lighters of various diverse types may be filled from the receptacle R 45 and that the invention, in no manner at all, is to be limited to use with a conventional lighter of the type shown.

The receptacle R may be of such size as is suitable or desirable. Ordinarily, the capacity 50 thereof is relatively large so that a large number of lighters may be filled from a single charge supplied thereto. As stated, said receptacle R is adapted to be supported more or less permanently on a store table, counter or the like and, to

this end, there may be utilized a suitable weighting arrangement. Or, the receptacle may be equipped with brackets or the like to be fastened to the supporting surface.

While the invention has been described with 5 respect to a certain particular preferred example which gives satisfactory results, it will be understood by those skilled in the art after understanding the invention, that various changes and modifications may be made without departing from 10 the spirit and scope of the invention and it is intended therefore in the appended claims to cover all such changes and modifications.

What is claimed as new and desired to be secured by Letters Patent is:

1. Apparatus for injecting liquid fuel into the fuel receptacle of a pyrophoric lighter, comprising a casing adapted to be supported in vertical position, a fixed tube depending from above the top wall of said casing to a point therein adjacent the 20 bottom thereof, threaded means for detachably securing the fuel receptacle of the lighter to the section of said tube disposed above said top wall, the space above said casing top wall being free from obstructions whereby the lighter may be 25 rotatably secured in position, said casing being supported in vertical position whereby the lighter fuel receptacle may be held thereabove by the upper end of said tube, and means operative while said casing and the lighter are thus positioned 30 for forcing liquid upwardly through said tube and thence into the lighter fuel receptacle.

2. Apparatus for injecting liquid fuel into the fuel receptacle of a pyrophoric lighter, comprising a casing adapted to be supported in vertical position, a fixed nipple carried by the top wall of said casing adjacent the mid portion thereof, a fixed tube depending from said nipple and within said casing to a point adjacent the bottom of said casing, said nipple comprising an externally threaded 40 upper section for detachable threaded engagement with the fuel receptacle of the lighter, the space above said casing top wall being free from obstructions whereby the lighter may be rotatably secured in position, said casing being supported in vertical position whereby the lighter fuel receptacle may be held thereabove by said nipple, and means operative while said casing and the lighter fuel receptacle are thus positioned 45 for forcing liquid upwardly through said tube and 50 thence into the lighter fuel receptacle, said means comprising a pump formed by a side wall of said casing.

LOUIS V. ARONSON.
